[57] CLAIM

The ornamental design for a mini-fence joint and inlay device, as shown and described.

DESCRIPTION

FIG. 1 is a perspective view of my mini-fence joint and inlay device, showing my new design;

FIG. 2 is a top view thereof;

FIG. 3 is a bottom view thereof; and,

FIG. 4 is a front elevational view thereof, the rear elevational view being a mirror image thereto.

FIG. 1

FIG. 2

FIG. 3

FIG. 4
